ELECTRIC CIRCUIT TESTING DEVICE

Michal Mohylowski, Kansas City, Mo.

Application August 13, 1951, Serial No. 241,591

5 Claims. (Cl. 324—51)

1

The present invention relates to electric circuit testing devices, and has for its object the provision of a device capable of generating an electric spark as an indicator that the circuit is broken in a wire or any electric apparatus.

A still further object of the present invention is an electric testing device of the character indicated having in its assembly solenoid for the purposes of causing a gap in the wire running through the device, whereby a spark may be engendered so as to provide a visual means indicating that the electric circuit tested is in a broken condition.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views:

Fig. 1 is a side elevational view of the present device;

Fig. 2 is an enlarged longitudinal cross sectional view therethrough;

Fig. 3 is an enlarged cross sectional view on a transverse plane, the view having been taken on line 3—3 of Fig. 2;

Fig. 4 is a longitudinal cross sectional view through the electro-magnetic core, and a wire in a slidible relation therewith, constituting parts of the present invention; and

Fig. 5 is a fragmentary longitudinal cross sectional view through the device with the wire terminals in an operative position, separated due to the action of the electromagnet, for establishing a gap therebetween and thereby for engendering electric spark.

Referring in detail to the present drawing there is shown therein a tapering handle 10, from the free, narrower end of which probing pin 11 projects. Said pin 11 is integrally formed with wire 12. Said wire adjacent the free narrow end of said handle 10 is provided with threads 13 for engaging nut 14. The inner end of said wire 12 is connected with terminal 15, resting upon the inner end of said handle 10.

Integrally formed with said inner end of handle 10 is collar 16, which in conjunction with the body portion of handle 10 defines a socket into which one end of transparent tube 17, made of glass or plastic, is receivable. Screws 18 passed

2

through said collar 16 engage said tube 17 and rigidly connect the same with handle 10. Portion of said tube is coated as at 17', which renders the remaining portion of the tube transparent, through which portion electric spark hereinafter mentioned may be observed.

In a longitudinal alinement with wire 12 is rod 19 of magnetic material, which by its lower end carries another terminal 20. The upper end of said rod 19 enters sleeve 21, which is in a frictional engagement with tubular core 22 made of magnetic material. Said sleeve 21 at its lower end is provided with an integrally formed flange 23 which remains in contact with flange 24 integrally formed with the lower end of core 22.

Encompassing said rod 19 and interposed between said terminal 20 and flange 23 is coil spring 25, the ends of which are preferably soldered to said terminal 20 and flange 23, respectively. Said coil spring 25 urges terminal 20 toward terminal 15 and maintains the same in a mutual contact.

The opposite end of said core 22 connects with cylindrical block 26, which is positioned within the opposite end of tube 17, forming a plug therefor, and is rigidly held therewith by means of a plurality of screws 27.

Either in a frictional or threaded engagement in a transverse relation with block 26 is metallic socket member 28, the adjacent portion of tube 17 being apertured to provide access to said member 28.

Coil 29 is wound around said core 22. One end of said coil 29 is connected or soldered to flange 24, while the other end thereof is passed through said block 26 and is connected or soldered with said socket member 28.

Disengageably receivable within said socket member 28 is rod 30, which is provided with tubular shield 31. Connecting with said rod 30 is flexible wire 32, which, within handle 33 connects with probing pin 34.

To test an electric circuit in any given wire or electric apparatus, it is first necessary to insert rod 30 within socket member 28. Thereupon probing pins 11 and 34 are driven into the wire tested or any given apparatus. If the tested wire or other electric apparatus is broken, in that event the electric current rather than to pass through the tested wire or apparatus will pass through pins 11 and 34 and the parts of the device intermediately thereof. The electric circuit passing through the device will energize coil 29 and core 22 thereby causing, due to the electro-magnetic action, the shifting of rod 19 within core 22 and collar 21 and against the tensioning

action of coil spring 25. The shifting of rod 19 in an upward direction will necessarily lift terminal 20 from terminal 15, separating the two and forming a gap therebetween. Due to the gap electric spark will flow from one terminal to the other, which observed through transparent portion of tube 17 will give a visual indication that the tested wire or other electric apparatus was broken intermediately of the probing pins 11 and 34, thereby localizing the seat of trouble as being in the area intermediately of said probing pins.

If on the other hand the tested area has no broken wire or a short circuit the electric circuit will flow normally through the wire or electric apparatus which is tested, its intensity through the device being not of a sufficient degree to energize the solenoid 22. This in turn will cause terminals 15 and 20 to continue to be in contact, due to the normal action of coil spring 25, thereby no gap therebetween will be established and no spark will be engendered to give visual indication of any trouble in the tested wire or apparatus.

The detachability and substitution of wire 32 of greater length may be dictated by the distance at which probing pins 11 and 34 are to be placed upon the electric conduit or other electric apparatus to be tested.

While there is described herein a preferred embodiment of the present invention, it is nevertheless to be understood that minor changes may be made therein without departing from the spirit and scope of the invention as claimed.

What I claim as new is:

1. An electric circuit testing device comprising a tube, a handle attached to said tube and projecting therefrom in a mutually longitudinal relation, a probing pin extended through said handle in an axial relation, a terminal carried by the inner end of said probing pin and supported within said tube, an electro-magnetic core within said tube supported by the opposite end thereof, a coil around said core, said core being in an axial relation with said tube, a rod of magnetic material extended within said core by one of its ends, a terminal carried by the other end of said rod, a coil spring interposed between said core and said last named terminal for normally maintaining the latter in contact with said first named terminal, said coil and said coil spring being connected, and another probing pin, said latter pin being attachable to the said opposite end of said tube, said probing pins, terminals, coil, coil spring and rod being in a circuit, when an electric current is passed through said circuit said coil being adapted to energize said core for shifting said rod against the action of said coil spring for separating said terminals and for establishing a gap therebetween, an electric spark being engendered through said gap when the electric circuit is maintained.

2. An electric circuit testing device comprising a transparent non-conducting tube, a handle of non-conducting material attached to said tube and projecting therefrom in a mutually longitudinal relation, a probing pin extended through said handle in an axial relation, a terminal carried by the inner end of said probing pin and supported within said tube, an electro-magnetic core within said tube supported by the opposite end thereof, a coil around said core, said core being in an axial relation with said tube, a rod of magnetic material extended within said core by one of its ends, a terminal carried by the

other end of said rod, a coil spring interposed between said core and said last named terminal for normally maintaining the latter in contact with said first named terminal, said coil and said coil spring being connected, and another probing pin, said latter pin being attachable to the said opposite end of said tube, said probing pins, terminals, coil, coil spring and rod being in a circuit, when an electric current is passed through said circuit said coil being adapted to energize said core for shifting said rod against the action of said coil spring for separating said terminals and for establishing a gap therebetween, an electric spark being engendered through said gap when the electric circuit is maintained, the spark being visible through said tube.

3. An electric circuit testing device comprising a tube, a handle, said handle being provided with a socket at one end thereof, said tube being receivable by one of its ends within said socket and being rigidly attachable to said handle, a probing pin extended through said handle in an axial relation with said tube, a terminal carried by the inner end of said probing pin, said terminal resting upon the bottom of said socket, an electro-magnetic core within said tube supported by the opposite end thereof, a coil around said core, said core being in an axial relation with said tube, a rod of magnetic material extended within said core by one of its ends, a terminal carried by the other end of said rod, a coil spring interposed between said core and said last named terminal for normally maintaining the latter in contact with said first named terminal, said coil and said coil spring being connected, and another probing pin, said latter pin being attachable to the said opposite end of said tube, said probing pins, terminals, coil, coil spring and rod being in a circuit, when an electric current is passed through said circuit said coil being adapted to energize said core for shifting said rod against the action of said coil spring for separating said terminals and for establishing a gap therebetween, an electric spark being engendered through said gap when the electric circuit is maintained.

4. An electric circuit testing device comprising a tube, a handle, said handle being provided with a socket at one end thereof, said tube being receivable by one of its ends within said socket and being rigidly attachable to said handle, a probing pin extended through said handle in an axial relation with said tube, a terminal carried by the inner end of said probing pin, said terminal resting upon the bottom of said socket, a plug within the opposite end of said tube, an electro-magnetic core within said tube supported by said plug, a coil around said core, said core being in an axial relation with said tube, a rod of magnetic material extended within said core by one of its ends, a terminal carried by the other end of said rod, a coil spring interposed between said core and said last named terminal for normally maintaining the latter in contact with said first named terminal, said coil and said coil spring being connected by their inner ends, another probing pin, said latter pin being attachable to said plug, and connecting means within said plug between the opposite end of said coil and said last named probing pin, both of said probing pins, terminals, coil, coil spring and rod being in a circuit, when an electric current is passed through said circuit said coil being adapted to energize said core for shifting said rod against the action of said coil spring

for separating said terminals and for establishing a gap therebetween, an electric spark being engendered through said gap when the electric circuit is maintained.

5. An electric circuit testing device comprising a tube, a handle, said handle being attachable to one end of said tube in a longitudinal relation, a probing pin extended through said handle, a terminal carried by the inner end of said probing pin, said terminal resting upon the end 10 of said handle and within said tube, a plug positioned within the opposite end of said tube in a rigid relation therewith, an electro-magnetic core within said tube supported by said plug, a coil around said core, a rod of magnetic material extended within said core by one of its ends, a terminal carried by the other end of said rod, a coil spring interposed between said core and said last named terminal for normally maintaining the latter in contact with said first named 15 terminal, said coil and said coil spring being connected by their inner ends, a socket member embedded within said plug, the opposite end of said

coil being extended within said plug and connected with said socket member, and another probing pin, said latter probing pin being detachably receivable by one of its ends within 5 said socket member, both of said probing pins, terminals, coil, coil spring, rod and socket member being in a circuit, when an electric current is passed through said circuit said coil being adapted to energize said core for shifting said rod against the action of said coil spring for separating said terminals and for establishing a gap therebetween, an electric spark being engendered through said gap when the electric circuit is maintained.
